UNITED STATES PATENT OFFICE.

HARLIE O. PUTT, OF ELKHART, INDIANA.

ELECTROMAGNETIC CIRCUIT-INTERRUPTER.

1,302,847.

Specification of Letters Patent.

Patented May 6, 1919.

Application filed December 28, 1917. Serial No. 209,295.

To all whom it may concern:

Be it known that I, HARLIE O. PUTT, a citizen of the United States, residing at Elkhart, in the county of Elkhart and State of Indiana, have invented a new and useful Electromagnetic Circuit-Interrupter, of which the following is a specification.

The object of my invention is to provide a magnetically controlled and operated interrupter which will automatically "time" itself to the peak of the primary current wave regardless of the direction of rotation or speed of magneto. It is also my object to provide an interrupter that may be installed at any point distant from the magneto or ignition dynamo, such as the instrument board of an automobile or aeroplane, thereby facilitating ease of inspection, adjustment or replacement, or it may be installed on the magneto itself at any convenient or desirable point.

I have primarily constructed this electromagnetic current interrupter to operate on the primary current of any ordinary high tension or compound wound magneto or ignition-dynamo armature, or on current from simple or single-wound armatures, although it is obvious that it will operate on a battery current if a suitable current contact controlling device is mounted on and rotates with the magneto armature shaft, so as to cause battery current to flow at or near the firing or ignition instant.

Its flexibility of installation, accessibility, simplicity of principle and construction, efficiency and accuracy of operation and low manufacturing cost, I regard of great value.

Figure 1 is a front view of the interrupter partly in section;

Fig. 2 is a sectional view on the line 2—2 of Fig. 1; with a circuit diagram showing connections with condenser;

Fig. 3 is a plan view of the magnet pole laminæ, showing general form.

Like characters of reference designate like parts throughout the several views.

Referring to the accompanying drawings:

The insulated contact screw terminal or post *a*, Fig. 1, carries an adjustable contact screw *b*. The laminated pole pieces *c* and *c'* project through the non-magnetic plate or base *d* to which they are secured. The armature *e* of magnetic material is secured to a flat spring *g* which is attached to lower pole piece *c'* by means of screw *h*. This armature *e* carries two adjusting screws *J*

and *J'*, which are adjusted in position by set screws *K* and *K'*. Contact arm *L* (which also acts as an armature) is also secured to spring *g* at the opposite end from that to which armature *e* is attached and carries a contact point at its other extremity. As illustrated, my armature *e* is of relatively heavier material than the second armature or contact arm *L*.

Adjusting screw *J'* passes through a clearance hole in armature or contact arm *L* and screws into armature *e*. The head of this screw strikes against arm *L* and acts as a stop for armature *e* in normal position.

Adjusting screw *J* threads through armature *e* to within a short distance of armature or contact arm *L* and is locked in position by set screw *K*.

As illustrated in Fig. 2, I provide an electro-magnet coil *m*, and a core *n* of soft magnetic material rigidly attached to members *c* and *c'* so as to form a good magnetic connection with same.

The tension of spring *g*, Fig. 1 is such as to pull armature *e* away from pole pieces *c* and *c'*, and by means of adjusting screw *J'*, pulls armature or contact arm *L* toward pole pieces *c* and *c'* on the opposite side, until contact points *p* are "closed".

Armature *e* and armature or contact arm *L* rest normally in this position.

Armature or contact arm *L* has sufficient spring tension toward pole pieces *c* and *c'* to close contact points *p* irrespective of the spring tension of armature *e*.

When coil *m*, Fig. 2, is energized by the primary current wave of an ignition dynamo or magneto flowing through contact points *p* causing poles *c* and *c'*, Fig. 1, to become magnetized they attract armature or contact arm *L* tending to cause contact points *p* to contact more firmly. At the same time armature *e* is attracted toward poles *c* and *c'* and is free to move toward them a definite degree or distance without affecting contact arm *L* thereby gaining momentum before adjusting screw *J* strikes armature or contact arm *L*. When member *J* strikes armature or contact arm *L* it suddenly opens the primary circuit at contact points *p* and thereby deenergizes poles *c* and *c'*.

Spring *g* then instantly returns armature *e* and contact arm *L* to normal position, as shown in Fig. 1, adjusting screw *J'* striking against contact arm *L* to firmly close contact points *p*.

As the speed of the magneto increases, the consequent output or value of primary current increases, hence the pull or attractive force of poles c will increase with the speed of the magneto. By providing the device shown in Fig. 1, I obtain automatic magnetic control of the tension of contact arm L in direct proportion to the strength of the primary current wave by the magnetic action on armature or contact arm L inasmuch as the stronger the poles c and c' become, the more firmly does arm L hold contact points p closed. In other words, contact points p are caused to contact more firmly at high magneto speeds. By virtue of armature e being of heavier magnetic material, it still is strong enough to force arm L away from poles c .

It is understood that the relative spring 20 tension of contact arm L and armature e and also the weight of their respective elements must be properly proportioned, but once adjusted, the adjustment remains permanent for all speeds of magneto.

25 At low magneto speeds the armature e will lag, producing a somewhat retarded ignition spark. As the magneto speed increases, armature e acts with less lag thereby advancing the ignition spark. This advance 30 and retardation is proportional to the speed of magneto within certain limits, but is automatic.

To illustrate the operation of my invention, assume my structure is adjusted to respond to a current value of minimum degree. 35 As the magnetic attraction of the poles of the electro-magnet reaches a value sufficient to move the armature from its state of rest, or normal position, toward the poles of said 40 magnet, the armature will "lag" behind the "pull" of the magnet to a certain degree, because of the weight of this armature and the spring tension factor being so near the same value as the magnetic attractive factor. 45 Also, a further degree of "lag" is caused by the natural reluctance of the core of the electro-magnet, so that by the time the armature has moved toward the poles a certain degree, it encounters, through its adjustable screw, 50 resistance to further movement, in the effort to force contact arm L away from the magnet poles.

55 Armature or contact arm L possesses a definite degree of elasticity or "cushion" in relation to armature e , but by virtue of armature e being heavier, its inertia forces contact arm L away from magnet poles c and c' and the fixed contact member, thereby opening the circuit, of which the electro- 60 magnet is a part. The instant of break of the contacts will occur later than the instant of peak value of the current wave inducing the movement. This retardation is comparatively slight, however, but is of added value 65 to the efficiency of the instrument, in that it

effects a feature that is of value in gas engine operation, namely automatic retardation at low engine speeds.

As the speed of the engine and magneto increases, the resultant primary current 70 value increases. Hence the attractive force of the magnet poles increase, which causes the contact arm L to make a firmer contact with the fixed contact member, and also stiffening the action of the contact arm in relation to the armature, so that as the armature responds more quickly to the increased attractive force of the magnet poles, it attains greater momentum, and through the 75 aforementioned adjusting screw, encounters 80 a less resilient contact arm, thereby obtaining a quicker break at the contact points. However, the resilient action of the armature or contact arm L in relation to the armature e in returning to normal position 85 or state of rest is effective, in that it cushions the armature, which effect makes it more readily responsive to the succeeding attractive effort, especially at high speed. The greater the degree of rigidity of armature or contact arm L as occasioned by the 90 increased magnetic action on same by the electromagnet, the greater the degree of rebound it will effect on the armature; hence, 95 the quicker will the armature attain its normal position, and consequently, through its connection with the contact arm, the quicker will the contact points be closed.

To further increase the effectiveness of this factor and to offset the effect of residual magnetism in the poles of the electro-magnet, I project the poles c and c' through a non-magnetic disk or plate d , which in the structure illustrated in the drawings serves as a base or mounting for the instrument. 100 This plate is preferably of brass or other suitable material. At the instant of separation of the contact points, a current is induced in this plate, which current flows in a direction around each magnet pole, tending 105 to produce a magnetization of said poles of opposite polarity to that of the polarity induced by the primary current wave. This current induced in the plate only flows around the magnet poles for a period of time 110 corresponding to the period of demagnetization of said poles, due to the opening of the circuit of which the electro-magnet is a part. The effect is to completely eradicate any 115 residual magnetism that may be momentarily present in the poles, and through the repulsive action on the armature at this instant, causes the armature to attain its normal position more quickly. As will be understood, the armature just prior to the instant of the break of the circuit has become 120 a magnet by induction, the polarity of which is opposite to that of the electro-magnetic poles, but when the actual break of contact points is effected, and for the instant, the 125 130

- magnet poles reverse polarity, and the polarity being the same as that of the armature, the armature would be repulsed. The armature, it will be understood, would be in closest proximity to the magnet poles at this instant, while the contact arm L would be relatively distant from them. Also the armature e is of sufficient weight and quality of material to enhance this magnetic inductive effect, while the contact arm L is so designed as to be practically unaffected by any repulsive effect due to the nature and mass of its element, though the above-mentioned reversal of polarity of the magnet poles momentarily causes an attractive effort, though comparatively slight, of the contact arm L, which effect is in co-operation with the repulsive movement of the armature e.
- At low magneto speeds the resultant residual magnetic factor would be comparatively less than at high magneto speeds, due to the variation of value in the primary current through the electro-magnet coil. Also, the resultant inductive effect in the non-magnetic plate around the magnet poles would be less due to the fact that the intensity of magnetic flux in the poles would be less, but the armature would have more time to get back to normal at the above mentioned low magneto speeds.

All of the above described facts act in co-operation with the functional movement of applicant's structure to secure the automatic adjustment of his structure to the variable values and frequencies of the current actuating same.

The self-induction of the electro-magnetic coil at the instant of the break of the circuit is completely absorbed or neutralized by the condenser (which is connected across the break or point of contact in a manner familiar to those skilled in the art) as is also the self-induction of the whole primary circuit including the primary winding on the magneto armature. This is necessary in order to prevent excessive arcing of the contact points at the instant of break.

The automatic timing of my structure to or near the peak of the primary current wave of any standard high or low tension magneto on the market will be understood by the foregoing explanation.

It is understood that where a greater degree of advance and retardation is required it must be acquired through some mechanical means connected between the magneto and the motor on which it is installed, or in other words, by varying the position of the magneto armature in relation to the piston travel.

In mechanically operated circuit-breakers the contact arm or spring commonly employed does not close contacts quickly enough at high speed to insure saturation

of the armature core with magnetic flux owing to the violence of the impact with the cam surface, which causes "missing" unless excessive spring tension is employed which rapidly wears both contact points and cam surfaces.

It will be seen that in my invention the degree of firmness of contact is increased proportionately with the magnetic strength of poles e, Fig. 1, acting on contact arm or spring L and the magnetic strength of poles e is, of course, proportional to the speed of magneto, thereby securing an automatic adjustment.

In mechanically operated interrupters, the opening of the contact points at low speed is necessarily slow. It is extremely desirable to instantaneously open the contact points at all speeds, but at low speeds especially, in order to produce the maximum inductive effect in the magneto armature winding, thus generating a hotter and more efficient spark.

In my invention the rapidity or "speed" of interrupter at low magneto speeds is practically instantaneous in comparison with the speed of mechanically operated interrupters.

My invention is an improvement over prior mechanical circuit interrupters in that it may be installed at any point distant from the magneto or ignition dynamo, where it may be more easily inspected, adjusted or replaced, as for example on the instrument board of an automobile or aeroplane, instead of being attached to or driven direct by some rotating or moving part of a magneto, such as the armature shaft, which would make accessibility very difficult and in most cases subject the contact points to dirt and oil and thereby cause trouble. A further advantage attained by my construction is that repairs may be made without returning the whole magneto or ignition system to the factory for adjustment as has heretofore usually been necessary. I have successfully operated this interrupter fifteen feet distant from the magneto. The advantage of this factor is apparent as its installation is not restricted to any particular location.

I claim—

1. In an electro-magnetic circuit interrupter, the combination of a non-magnetic plate, an electro-magnet having its poles projecting through the aforesaid plate, a spring secured to one of the pole members, an armature of magnetic material secured to one end of the aforesaid spring, a contact arm secured to the other end of said spring, said contact arm acting as an armature of lighter weight than the first mentioned armature, a contact member with which the contact arm mentioned is arranged to electrically connect, means adjustably connecting the aforesaid contact arm and armature,

and an electric circuit electrically connected with the aforesaid apparatus and which is interrupted by the movement of the contact arm, substantially as described.

- 5 2. In an electro-magnetic circuit interrupter, the combination of a non-magnetic inductive plate, an electro-magnet having its poles projecting through said plate, a plurality of armatures mounted in spaced relation to the poles of the magnet, means adjustably connecting the aforesaid armatures to maintain same in spaced relation as required, a contact member with which one of the armatures contacts, and an electric circuit electrically connected with the aforesaid apparatus and adapted to be interrupted by the movement of the armatures, substantially as described.

- 20 3. In apparatus for interrupting an electric circuit, the combination of an electro-magnet, an armature of relatively heavy material controlled by the electro-magnet, a second armature and contact member controlled by the before-mentioned armature 25 and electro-magnet, a non-magnetic inductive plate through which the poles of the electro-magnet project, and an electric circuit electrically connected with the above-described apparatus, said circuit being interrupted by the movement of the second armature and contact member, the operation of said last-mentioned member being automatically controlled by the generated or energizing current wave, substantially as described.

- 35 4. In an electro-magnetic circuit interrupter, the combination of an electric circuit, a non-magnetic inductive plate, an electro-magnet having its poles projecting through said plate, a plurality of armature members mounted in spaced relation to the poles of the magnet, means adjustably connecting

said members, the interrupting of the aforesaid circuit being automatically and magnetically governed to break the circuit at the most efficient point of the generated current 45 wave, substantially as described.

5. In a circuit interrupter, the combination with a magneto and an electric circuit, of an electro-magnet in said circuit, an armature of relatively heavy material mounted in spaced 50 relation to the poles of the magnet, a contact member mounted in spaced relation to the poles of the magnet and adapted to interrupt the electric circuit when the armature is attracted by the magnet, and means adjustably 55 connecting the aforesaid armature and contact member, substantially as and for the purposes described.

6. An electro-magnetic circuit interrupter adapted to operate on a current of intermittent or alternating values, comprising an electromagnet; laminated pole-pieces mounted on the magnet; a plurality of armatures supported in spaced relation from one pole of said magnet; one of said armatures being 60 of comparatively light resilient material and operating as a contact arm; means adjustably connecting the aforesaid armatures to maintain same in the desired adjusted spaced relation; a non-magnetic inductive plate interposed between the electro-magnetic coil and the aforesaid armatures; the aforesaid pole pieces projecting through said plate to provide means to compensate the self-induction 65 of the electro-magnetic coil, to eliminate the residual magnetism in the said poles of the electro-magnet, and to effect a repulsive effect on the armature toward its normal position; and an electric circuit arranged substantially as described. 70 75

HARLIE O. PUTT.
